UNITED STATES PATENT OFFICE

HARRY ABRAHAM STERN, OF NEW YORK, N. Y.

ASH TRAY

Application filed January 13, 1928. Serial No. 246,463.

This invention relates to ash trays and the like having for its object to provide means within the body of the said tray to flicker or scrape the ashes from the end of a cigar or cigarette.

One of the objects of my invention is to provide an ash tray having an upstanding blade either permanently attached thereto or separable therefrom and adapted to be used to flicker or scrape the ashes from a cigar, cigarette or pipe bowl.

A further object of my invention is to provide an ash tray equipped with a blunt edge, knife like blade extending somewhat above the top of the tray, and either permanently attached to the bottom or separable therefrom and employed to flicker or scrape the ashes from a cigar, cigarette or pipe bowl.

To enable others skilled in the art to more fully comprehend the underlying features of my invention, reference is had to the accompanying drawing forming a part of this specification in which

Fig. 1 is a perspective view illustrating a preferred form of the invention.

Fig. 2 is a detail view showing one means of attaching the blade to the bottom of the tray.

Fig. 3 is a perspective view of a modified form of the invention.

Referring now to the drawings, 5 designates the body of an annular, shallow tray having a top rim 6 formed therewith, preferably of metal, and to which is attached a cigar or cigarette rest 7, extending over the edge of said rim. While I have shown and referred to an annular tray, it will be understood that an elliptical, square or other shape tray may be employed.

In the form of the invention illustrated by Fig. 1, there is provided a flat blade 8 positioned substantially centrally of the bottom 9 of the tray, said blade 8 being soldered or otherwise permanently attached as at 10 to the bottom. Wherever I use the term blade or blade-like I wish it to be understood that the same is intended to cover as well a structure made of wire, the periphery of which will be substantially the periphery of the blade-like portion herein described. The

blunt edges 11, 12 of the blade taper toward the blunt point 13 of said blade which is of a height to extend considerably above the rim. The shallow tray body thus affords a receptacle for the ashes dropped therein or removed by brushing or flickering the same from the cigar, cigarette or pipe. The blade also affords a means for scraping a pipe bowl if so desired.

Instead of soldering the blade to the bottom of the tray, in Fig. 2 I have shown a modified form of attaching said blade which consists in providing two tongues 14, 15 on opposite sides of the straight bottom, said tongues being adapted to be passed through suitable apertures in the bottom of the tray and flattened or clinched.

In the modified form of the invention shown by Fig. 3, the shallow tray 5^a is provided with a removable inner receptacle 16 preferably of glass whereby it may be easily cleaned. The receptacle 16 is equipped with opposed grooves 17 for receiving the ends of an inverted T-shaped flat bar 18 which may be inserted and removed when it is desired to clean the inner receptacle. The bar 18 is formed with an upstanding blade 19 similar in construction to the blade 8, illustrated in Fig. 1, and is of course employed for the same purposes. This form of the invention is easily assembled, requires no soldering and may be kept clean with very little difficulty. Other means may be resorted to for attaching the inverted T-shaped blade either to the inner receptacle or to the outer tray.

While I have shown and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the subject matter being claimed.

Having shown and described my invention, what I claim as new and desire to secure by Letters Patent is:—

1. A device of the class described comprising a shallow tray, a removable receptacle for

said tray, said receptacle having opposed grooves, and a separable plate having a single flat upright blade seated in said grooves.

5 2. A device of the class described comprising a shallow tray, a removable receptacle for said tray, said receptacle having opposed grooves, a T-shaped flat plate having the ends of the cross piece seated in said grooves, and the upright stem forming a single flat 10 blade integral with the plate extending above the top of the tray.

15 3. A device of the class described comprising a shallow tray, a removable receptacle for said tray, said receptacle having opposed grooves, an inverted T-shaped, flat plate having its ends seated in said grooves, said vertical portion of said plate being in the form 20 of a knife blade, the edges of said blade being blunt and constituting means for flickering or scraping the ashes from a cigar, cigarette or pipe.

In testimony whereof he has affixed his signature.

HARRY ABRAHAM STERN.
